CIRCUIT INTERRUPTER

James M. Wallace, Braddock, and Herbert L. Rawlins, Wilkinsburg, Pa., assignors to Westinghouse Electric Corporation, East Pittsburgh, Pa., a corporation of Pennsylvania

Original application January 16, 1941, Serial No. 374,686. Divided and this application October 18, 1945, Serial No. 623,125

17 Claims. (Cl. 200—89)

1

This invention relates generally to circuit interrupters, and more specifically to operating mechanism and control means for circuit interrupters.

This application is a division of applicants' copending application Serial No. 374,686, filed January 16, 1941, now Patent No. 2,475,765, July 12, 1949, on Circuit Interrupters.

Although this invention is herein specifically disclosed in connection with an automatic reclosing circuit breaker capable of automatic lockout in response to a predetermined number of closely successive interrupting operations, wherein the invention has certain novel features of co-operation providing certain new and useful results, it will be appreciated that certain features of the invention may also be useful in connection with other types of circuit breakers, and even apparatus other than circuit breakers.

In order to obtain better coordination with other breakers of the automatic reclosing type, it is desirable that the breaker have an inverse time characteristic, which preferably shall be the same for all trippings of the breaker.

Accordingly, one object of this invention is to provide novel means for providing an inverse time delay tripping characteristic for a circuit breaker.

Another object of this invention is to provide novel trip control means for an automatic reclosing circuit breaker which shall provide the same tripping characteristics on all trippings of the breaker.

Another object of this invention is to provide in a circuit breaker of the type described, novel mechanism for controlling the opening and closing movements of the breaker.

Another object of this invention is to provide in a breaker of the type described, novel means for maintaining the breaker contacts separated in response to a predetermined number of closely successive reclosures thereof.

Another object of this invention is to provide novel means for delaying circuit opening and closing movements of an automatic reclosing circuit breaker for different times, respectively.

Another object of this invention is to provide novel means for delaying circuit opening and closing movements of an automatic reclosing circuit breaker with provision for rendering the delay means ineffective just prior to separation and engagement of the breaker contacts, respectively.

These and other objects of this invention will become more apparent upon consideration of

the following description of preferred embodiments thereof when taken in connection with the attached drawings, in which:

Figure 1 is a substantially central, longitudinal sectional view of a circuit breaker embodying this invention.

Fig. 2 is a view like Fig. 1 only showing the position of the parts after a circuit interrupting operation.

Fig. 3 is a partial, substantially central, longitudinal section view of the breaker shown in Figs. 1 and 2, and taken substantially at right angles to the section of Figs. 1 and 2.

Fig. 4 is a view similar to Fig. 1, showing a portion of the upper end of the breaker with the parts positioned to lock the breaker contacts open.

Fig. 5 is a view of a modified form of interrupter operating mechanism per se, with certain parts thereof in section.

Fig. 6 is a partial side elevational view of the mechanism shown in Fig. 5.

Fig. 7 is a partial elevational view of the mechanism shown in Fig. 5, looking at the opposite side thereof, and

Fig. 8 is an elevational view, partly in section, of a still further modified form of circuit breaker operating mechanism.

The several embodiments of this invention herein disclosed, are adapted to be mounted in an insulating casing 2 having an upper terminal cover assembly 4, and a lower terminal assembly 6, which are substantially like those disclosed in applicants' copending application

Serial No. 346,300, filed July 19, 1940, now Patent No. 2,318,421, May 4, 1943, and assigned to the same assignee as this invention. Accordingly, for a more complete description of these parts, and for a full understanding of their function, reference is hereby made to the above-mentioned copending application.

In general, the insulating housing 2 is tubular or cylindrical in form, and is provided with an open top and a closed bottom. An intermediate portion of the casing 2 is adapted to have a supporting bracket 5 secured thereto, for supporting the breaker in operative position. The upper cover terminal assembly 4 includes the cover 8, having a diametrically extending hollow portion for the reception of certain parts of the breaker operating mechanism. The cover 8 is also provided with a peripheral flange 10 adapted to be seated on the open end of casing 2, and secured to an annular support 12 by any desired connecting means (not shown).

The lower terminal assembly 6 includes a bolt 14 of any desired conducting material, having an enlarged head 16 adapted to be positioned within casing 2, with packing material 18 between head 16 and the closed end of the casing. Conducting bolt 14 extends through a substantially central aperture in the closed end of casing 2, and is provided with a nut 20 for securing the bolt in operative position, with a washer 22 interposed between the nut and outer wall of the casing. As shown, a terminal strap 26 may be secured to bolt 14, for example, as by nut 28. The bolt 14 is also provided with a small central bore 24, adapted to have the outer end thereof closed by a removable drain plug 25, so that the casing may be drained when desired.

The circuit breaker and its operating mechanism are adapted to be supported from cover 8 by a pair of spaced supporting plates 30, secured to a portion of cover flange 10 overlying the interior of casing 2, for example, as by bolts 32, and these plates are connected by transversely extending integral frame portions 34 and 36. Spaced supporting plates 40, positioned substantially at right angles to supporting plates 30, are formed integral with transverse frame portion 36 and extend downwardly therefrom to support an interrupting chamber 42. The lower ends of supporting plates 40 are rigidly secured together by an integral web 38, having a socket 46 integral therewith for threadedly receiving one end of insulating tube 44, forming the side wall of interrupting chamber 42. Insulation tube 44 may be of any desired insulating material, preferably fiber or the like. The other end of insulation tube 44 is provided with an end terminal cap 48 threadedly engaged therewith, and conductively and resiliently associated with the enlarged head 16 of the lower terminal assembly bolt, by coil compression spring 50. Spring 50 is preferably of a resilient conducting material, such for example, as a copper alloy.

It will be noted that the interrupting chamber is provided with an outlet valve 52 and an inlet valve 54, a contact support 56 slidably mounted in a central aperture through transverse support frame member 38, together with a contact 58 mounted thereon, and a liquid director 60 having resilient lost motion with respect to contact 58. This interrupter chamber structure is substantially the same as that disclosed in the copending application of J. M. Wallace, Serial No. 374,684, filed January 16, 1941, and issued June 20, 1944, as Patent No. 2,352,048, assigned to the same assignee as this invention. The only difference in construction of the interrupter chamber of this invention over that disclosed in the copending application of J. M. Wallace, is that the contact support 56 is of insulation material for a purpose hereinafter to be described, and fixed contact 62 is mounted for limited relative movement with respect to end terminal cap 48, by a screw 64, secured to fixed contact 62 with the reduced intermediate portion thereof slidably extending through a central aperture in end cap 48, to provide for movement of contact 62 limited by the head of screw 64 and the contact itself, and normally biased upwardly by a coil compression spring 66 seated between end cap 48 and a shoulder formed on contact 62. Also, contact support 56 is formed with a notched portion 68 adjacent the upper end thereof for a purpose to be referred to.

In operation, interrupter 42 operates substantially in the same manner described in the co-

pending application of J. M. Wallace. This, in general, is as follows: When contact support 56 is moved upwardly to open the circuit, contact 58 moves away from fixed contact 62, after the head of screw 64 engages the lower terminal cap 48, to draw an arc therebetween. As soon as upward motion of contact support 56 is initiated, valve 52 moves therewith to close off the outlet of the interrupter casing. All this time liquid director 60 remains stationary, being held in the position shown in Fig. 1 by the spring 61 between contact support 56 and the director. As soon as the limit of the lost motion between the contact and director 60 is reached, the contact 15 will pick up the liquid director and move the same upwardly to thereby cause a stream of arc extinguishing fluid to flow through the arc to aid in extinguishing the same. After the circuit has been interrupted and contact support 56 is 20 moved downwardly to close the circuit, valve plate 52 will be moved therewith to open the chamber outlet, and check valve plate 54 will be raised to permit liquid to flow in the chamber inlet under the influence of gravity. As the contact 25 approaches closed position, liquid director 60 is first brought to a halt, and thereafter coil spring 61 is compressed and finally contact 58 engages fixed contact 62.

Contact support 56 is adapted to be disengaged 30 by an elongated contact rod 70, having one end thereof threadedly engaged in a bore in the upper end of contact support 56, and the other end thereof threadedly secured in the lower end of a socket member 72, forming one element of a contact locking means. As shown, the socket 72 is 35 hollow in form, and is provided with opposed slots through which are adapted to project the locking projections 76, of a pair of locking dogs 74 pivotally mounted at their lower ends on a pin 75 extending transversely of socket 72. The locking dogs 74 are proportioned so that the major portion of their mass lies on opposite sides, respectively, of a vertical plane through pivot 75, so that the dogs are biased by gravity to project 40 in a position with respect to socket 72. The upper end of socket 72 is adapted to fit into a bore provided in a cooperating inverted locking socket 80, having opposed side apertures 78 for the reception of lock projection 76 on the locking dogs, 45 to secure the two socket portions for movement together. It will be noted that the upper socket 80 is adapted to be slidably mounted in a sleeve 82 secured in a central aperture in upper transversely extending support plate 34. It will be 50 further noted that in the closed position of the contacts, the locking projections 76 on the locking dogs, are adapted to extend through apertures 78 of the upper socket member, to lie beneath and in engagement with the lower end of sleeve 82 to thereby maintain the contacts locked 55 in their closed circuit position.

The upper end of socket 80 is slotted to form bifurcations 84 for supporting therebetween an actuating pin 86. This pin is adapted to be engaged by a reclosing lever 88, pivotally supported as at 90 in the hollow portion of cover 8, and provided with a biasing spring 92 normally urging lever 88 in a counterclockwise direction about its pivot, to close the breaker contacts. The 60 outer end of reclosing lever 88 is inclined or curved to cooperate with the top of actuating pin 86. Biasing spring 92 also causes engagement of socket 80 with locking dogs 74 at a point displaced from dog pivots 75 so as to assist in biasing them relatively outwardly.

A substantially cylindrical solenoid core 94, of any desired magnetic material, is adapted to be slidably mounted at the lower end thereof on contact rod 70. The core 94 is provided with an outwardly projecting flange 96 at the lower end thereof, and with a counterbore 98 opening at the upper end thereof for the reception of a coil spring 100. A solenoid coil 102 is adapted to be supported between the transversely extending supporting plate portions 34 and 36, of the supporting frame, and this coil preferably is annular in form to provide a central bore therethrough in which is adapted to be mounted a cylindrical sleeve 104, preferably of a non-metallic material, such, for example, as fiber, a synthetic resin or the like.

It will be noted that solenoid core 94 slidably engages cylindrical sleeve 104 in a piston-like manner, and inasmuch as the entire mechanism is submerged in an arc extinguishing fluid which fills container 2 substantially up to the level L, and further in view of the fact that the upper end of cylinder sleeve 104 is closed, it will be obvious that upon energization of solenoid coil 102 sufficiently to raise core 94, that this movement of the core will be retarded by the dashpot action formed by the core and cylindrical sleeve 104. In other words, when core 94 is drawn upwards by solenoid coil 102, it is necessary that the liquid above the core in cylindrical sleeve 104 be forced out of the lower end of sleeve 104 past the relatively small clearance between the core and sleeve 104, which will necessarily delay the upward movement of core 104. This delayed action, of course, will be dependent upon the current passing through solenoid coil 102, so that the desirable inverse time characteristic is obtained for opening the breaker contacts.

As solenoid core 94 is moved upwardly in a circuit interrupting operation, it will be obvious that contact rod and contact 58 are maintained stationary by locking dogs 74, and that eventually in the upward movement of the core, coil spring 100 will engage the lower end of socket 72, so that upon continued upward movement of the core this spring will be compressed. The upper end of core 94 will eventually engage the lower end of upper socket 80, to move the same upwardly relative to lower socket 72, which is still held against upward movement by dogs 74, so that the lower edges of apertures 78 will eventually engage the outside edges of dogs 74 to act to cam locking dogs 74 inwardly, and permit contact rod 70 to be released. At this point there will be a positive drive connection between solenoid core 94 and contact rod 70, and because of the compressed condition of coil spring 100 which is of greater strength than contact closing spring 92, the contact 58 will be moved relatively quickly away from fixed contact 62, and this action will also be aided by any pressures developed by the arc within interrupter chamber 42. It should be noted that the contacts separate only a predetermined time subsequent to the initiation of movement of solenoid core 94, which time is predetermined by the dashpot action of the core and cylindrical sleeve 104, and dependent on the current through solenoid 102. This provides a time delay on tripping the breaker, which has been found experimentally to be as much as three seconds at minimum trip current values.

After the circuit has been interrupted, the contact rod 70 is free to be moved downwardly under the influence of contact closing spring 92, through

lever 88 acting on pin 86. However, between spaced supporting plates 40, adjacent to and just above the interrupting chamber 42, there are pivoted a pair of latch levers 106 (Fig. 3), on pivot pins 107 extending between the supporting plates, with each lever having a projection 109 adapted to engage the notch 68 at the upper end of contact support 56, to maintain the contacts open for a predetermined time period.

The latch levers 106 are biased towards each other to engage in notch 68 by a coil tension spring 108, connecting the levers at one side thereof. Accordingly, it will be seen that the contact closing spring 92 will immediately move the contact rod downwardly to a position wherein it is prevented from further movement by latch levers 106, and at this position the gap between contacts 58 and 62 will be sufficient to hold circuit voltage. Meanwhile, solenoid core 94 will travel downwardly very slowly due to the fact that it must draw oil into the space above it as it is moved downwardly under the influence of gravity, until the flange 96 on solenoid core 94 engages the upper inclined ends of latch levers 106, to spread these levers apart and release contacts 56 to permit the contacts to suddenly close. Consequently, it can be seen that a time delay is interposed between the actual interruption of the circuit and the reclosure of the breaker contacts by the dashpot action of solenoid core 94 in cylindrical sleeve 104. It has been determined that such a time delay in the reclosing operation may be made as long as ten to twelve seconds.

It will be apparent from the foregoing that there is incorporated in this embodiment of the invention a solenoid core which acts as one element of an inverse time current delay means for the circuit interrupting operation, and also provides a delay between the interrupting operation and reclosure of the breaker contacts. This embodiment of the invention further includes the feature of locking the breaker contacts in their closed circuit position, so that upon the occurrence of predetermined conditions in the circuit, an operating means for the contacts is first moved relative thereto to provide time delay in the interrupting operation and to stress a resilient means for biasing the contacts open, and only thereafter releasing the contact lock to permit them to separate.

The inner surface of transversely extending supporting plate 36 is provided with a relatively large cylindrical portion 111 adapted to receive flange portion 96 on solenoid core 94 when the core is adjacent the upper end of its path of movement. This cylindrical bore portion 111 is provided with a transverse outlet passage 110 connected to a cylinder 112, integral with upper and lower transverse supporting plates 34 and 36, with a resiliently biased check valve 114 controlling said passage to permit flow of liquid from cylindrical bore 111 into cylinder 112. A spring 116 is provided for biasing valve 114 to close passage 110, and a free floating piston 118 is preferably positioned in cylinder 112.

A lock-out lever 120 is secured to an operating shaft 124 extending transversely of the hollow portion of cover 8, with one end thereof extending through one wall of said hollow portion to have secured thereto a manually operable actuating lever 132. The lock-out lever 120 is biased for movement in a counter-clockwise direction with respect to the axis of shaft 124, by a spring 122 coiled about the shaft and engaged at its opposite ends with the cover 8 and lever 120, respec-

tively. The free end of lockout lever 120 is curved and positioned below actuating pin 86. The coil spring 122 of the lock-out lever 120 is considerably stronger than the contact reclosing spring 92, but is normally prevented from effecting operation of the contacts by a shoulder portion 126 integral with lever 120, being engaged by one leg 128 of a trigger lever pivotally mounted on the cover as at 129, and having the other leg 130 extending downwardly and provided with an inclined free end positioned over the top of cylinder 112.

Now, when the solenoid core 94 is moved upwardly as was previously described, to interrupt the circuit, when it reaches the end of its upward movement, flange portion 96 will act as a piston in cylinder portion 111 and force a predetermined quantity of liquid through passage 110, past check valve 114 and into cylinder 112, thereby raising piston 118 a predetermined distance in the cylinder, for example to the position shown in Fig. 2 of the drawings.

Now, when the contacts are reclosed by contact closing spring 92, if the fault has been removed from the circuit, piston 118 will slowly return to the position shown in Fig. 1 of the drawing, under the influence of gravity, and being delayed by the necessity of displacing the liquid below the piston past the relatively small clearance between the piston 118 and cylinder 112. However, if, after the first reclosure of the breaker contacts the fault still remains on the circuit, the contacts will again be opened in the same manner as for the first time, and this time flange 96 will act to force another predetermined quantity of liquid into cylinder 112 to advance piston 118 nearly to the top of cylinder 112. Upon a second closely successive reclosure of the breaker, if the fault has cleared by this time, the piston 118 will again slowly move to its normal position shown in Fig. 1 of the drawings. However, in the event that the fault has not cleared from the circuit, the contacts will again reopen, and this time flange 96 on solenoid core 94 will force sufficient liquid into the cylinder 112 to raise the piston 118 into engagement with the inclined end of trigger lever 130, to rotate this lever in a counterclockwise direction about its pivot 129, to release lockout lever 120 for movement in a counter-clockwise direction under the influence of its spring 122, and cause it to raise contact rod 70 against the bias of contact closing spring 92, as shown in Fig. 4, and thereby prevent further reclosures of the breaker contacts.

In order to reset the circuit breaker, it is necessary to exert a manual push on lever 132 to rotate it and lock-out lever 120 in a clockwise direction, until shoulder 126 on the lock-out lever is re-engaged by leg 128 of the trigger lever. Inasmuch as piston 118 will have in the interim descended from the position shown in Fig. 4 to its normal position shown in Fig. 1, the contacts may then be closed by reclosing spring 92 and thereby restored to normal operating condition.

The electrical circuit through the breaker may be traced from lower terminal assembly 6, to coil spring 50, lower interrupter casing terminal cap 48, fixed contact 62, movable contact 58 to a conductor 131 extending upwardly through a bore 133 provided off center through contact support 56 to one lead of solenoid coil 102. The other lead of solenoid coil 102 is adapted to be connected by a conductor 137 to cover 8, for example, as by bolt 32, and the other terminal of the breaker is adapted to be suitably mounted on

cover 8. It can, therefore, be seen that with this construction the solenoid coil 102 is connected in series relation in the circuit through the breaker, so as to be responsive to overload currents to cause movement of core 94 to interrupt the circuit.

Coordination between breakers of different ratings is readily obtainable with this device. In order to have different ratings of breakers, a different number of turns is wound for solenoid coil 102. Thus, for example, for a 20-ampere breaker approximately 250 turns may be required for the solenoid coil, while for a 40-ampere breaker only 125 turns may be required. Considering now a fault current flowing through the two breakers in series on a line; it will be obvious that twice as many ampere turns will be available for moving the solenoid core 94 in the 20-ampere breaker than in the 40-ampere breaker. Consequently, the core of the 20-ampere breaker will move much faster, so that this breaker will be tripped and clear the circuit before the solenoid core in the 40-ampere breaker can complete its stroke. The solenoid core in the larger breaker will therefore cease its upward travel and both solenoid cores will start to reset. Inasmuch as the breaker of a larger rating will have had the shorter core travel, its core will completely reset before the contacts of the smaller breaker are reclosed to subject the two breakers to overload current again. Accordingly, it can be seen that the larger rating breaker will never trip under the circumstances described above, and the smaller breaker will lock out and isolate the faulted circuit.

While certain of the features of the breaker illustrated in Figs. 1 to 4 are employed in the breakers shown in Figs. 5 to 7, other features peculiar to the breakers shown in Figs. 1 to 4 are not claimed herein but are claimed in applicants' previously mentioned copending application of which this application is a division.

The species of breaker illustrated in Figs. 5 to 7 of the drawings is adapted to be provided with an interrupting chamber like the interrupting chamber 42 of the species shown in Figs. 1 to 4, and it is also adapted to be mounted in operative relation with respect to a circuit breaker casing by a cover 8 adapted to clamp ears 135 on the mechanism supporting frame to the top wall at the open end of the casing. As shown in Fig. 5, the supporting frame for this circuit breaker includes a substantially rectangular upper supporting portion having a top wall 134, spaced integral side walls 136 and a bottom wall 138. Depending from this rectangular supporting portion are spaced supporting plates 140 adapted to be connected at their lower ends by an integral socket 141 for connection to an interrupting chamber like that shown in Figs. 1 and 2 of the drawings. The contact rod 142 in this embodiment of the invention is provided with stepped portions at the upper end thereof forming relatively stepped shoulders 144 and 146, for cooperation with a solenoid core 150, which, like core 94, is adapted to be slidably mounted in a cylindrical sleeve 156, to form a dashpot therewith, and have a hollow bore with a spring therein as in the embodiment of Figs. 1 to 4, so that the spring will engage shoulder 144, and the core engage the shoulder 146, substantially in the same manner as in the previously described embodiment.

The upper end of contact rod 142 is adapted to be slidably mounted in a plug member 148 secured to upper frame member 134 for closing

the upper end of cylindrical sleeve 156 and a solenoid coil 152 is adapted to be supported in the rectangular supporting frame portion.

Depending supporting plates 140 are each provided with aligned spaced guide slots 153 and 160 for receiving a guide pin 162 fixed on solenoid core 150, and a guide pin 164 fixed to contact rod 142, respectively. These guide pins are adapted to extend through their respective slots, and through slots provided in a locking lever 166 mounted at the outer side of the adjacent supporting plate 140, intermediate the ends thereof on a pivot pin 168. Locking lever 166 is normally biased by a spring 170 for movement in a clockwise direction on its pivot pin. Locking lever 166 is also provided with the slots for receiving guide pins 162 and 164, respectively, with the upper slot 171 for receiving pin 162 being flared outwardly in an upward direction, and including an outer inclined end 172 for a purpose to be described. Slot 174 is provided with an angularly extending portion 176 normally adapted to receive guide pin 164 on contact rod 142, for preventing upward movement of the contact rod. A pawl lever 178 is pivotally mounted at its lower end on guide pin 164 and is biased by a spring 181 towards a rack 188. The pawl lever 178 is provided with a pawl projection 179 adjacent the upper end thereof extending laterally from the lever and supported from the lever by a portion having inclined surfaces 180 and 182 adapted to be engaged by stationary cam pins 184 and 186, respectively. The rack 188 is secured to the upper end of a piston 190, slidably mounted in a cylinder 192 supported on the supporting frame socket 141. A light coil compression spring 194 is adapted to be positioned in the bottom of cylinder 192 for moving piston 190 to an extended position.

In the operation of this embodiment of the invention, upon the occurrence of an overload in the circuit, solenoid coil 152 moves core 150 upwardly until guide pin 162 on the core hits the inclined end 172 of slot 171 in the locking lever, thereby causing counter-clockwise rotation of the lever about its pivot 168, and releasing guide pin 164 on contact rod 142 to permit the solenoid to move the contact rod upwardly, aided, of course, by its spring which has been compressed by relative movement of the solenoid core and contact rod and by pressure in the interrupter chamber. After the circuit has been interrupted and the contacts are reclosed, preferably by a biasing means substantially like that shown in the first embodiment of this invention, as contact rod 142 moves downwardly, pawl projection 179 engages rack 188 to move the same downwardly a predetermined distance with the contact rod, which causes a time delay in reclosure due to the necessity of displacing liquid in the bottom of the cylinder 192 past the relatively small clearance between the piston and cylinder. Adjacent the end of the closing operation, inclined surface 182 on the pawl lever will engage cam pin 186 to cause the pawl lever to disengage rack 188, and allow the contacts to be suddenly closed. If the fault has cleared upon reclosure of the contacts, rack 188 will be raised to its extended position as determined by pin 185, working in slot 187 of the rack. However, if the fault has not cleared, the contacts will again be opened in the same manner as for the first interruption, and this time upon reclosure of the contacts, pawl lever 178 will move rack 188 and piston 190 down into cylinder 192 a further distance into close prox-

imity with the lower end of cylinder 192. If, after this second reclosure, the fault has cleared, rack 188 will again be reset by spring 194. However, if the fault has not cleared, the breaker contacts will again be opened, and this time upon attempted reclosure thereof, pawl lever 178 will move rack 188 downwardly until the upper end of slot 187 engages fixed pin 185, thereby preventing further closing movement of the breaker contacts.

In order to reset the breaker to normal operating condition it is necessary to raise contact rod 142 until inclined surface 180 on cam lever 178 engages cam pin 184, to disengage pawl projection 179 from rack 188, to thereby permit the rack to move upwardly, whereupon the contact rod 142 may be released, and the contacts reclosed as previously described.

In the modification of the invention shown in Fig. 8, there is illustrated a supporting frame comprising spaced supporting plates 196 joined by intermediate spaced transversely extending frame portions 197, 198 and 200, respectively. A solenoid coil 202 is adapted to be supported on the frame portion 197 between supporting plates 196. A contact rod 204 is secured to an enlarged rod portion 206 at the upper end thereof, to form a shoulder 208 adapted to be engaged by solenoid core 210 upon upward movement thereof. The solenoid core 210 is slidably mounted on the rod, and is provided adjacent the lower end thereof with a notch 212 adapted to be engaged by a latch 214 pivotally mounted on a time delay sleeve member 216, also slidably mounted on contact rod 204. The latch 214 is preferably supported on a pivot 218 on time delay sleeve 216, and is biased for movement to engage in notch 212 of the core, for example, as by a spring 220. Between transversely extending supporting plate portions 198 and 200, and also for a substantial distance below plate 200, there is provided a cylindrical wall portion integral with supporting plates 196 to form a cylindrical compartment 222 in which a time delay valve member 224 is adapted to work in a piston-like manner. Below supporting plate 200 a lock-out piston member 226 is adapted to operate. The time delay valve piston 224 is provided with passages 228 therethrough and a valve plate 230 biased to a position to close off passages 228, by a coil compression spring 232. The valve piston 224 is preferably fixed to time delay sleeve 216 for movement therewith. A check valve 234 is adapted to control an inlet passage 236 into the lower portion of cylinder compartment 222.

Lockout piston 226 is annular in form, and is provided with an inclined inner surface 238, for cooperation with a lockout lever 240, normally biased by a coil tension spring 242 to the position shown in Fig. 8 of the drawings.

The particular mechanism illustrated in Fig. 8 is, of course, adapted to be employed with an interrupter similar to the interrupter 42 shown in Figs. 1 to 4 of the drawings, and in conjunction with spring contact reclosing means also shown in the first described embodiment of this invention. In operation, when solenoid core 210 is attracted upwardly by solenoid coil 202, time delay sleeve 216 is carried along by virtue of the interconnection of latch 214 with core 210. This upward movement is therefore impeded to some extent by the necessity of liquid passing from the upper portion of cylinder compartment 222 to the lower portion thereof, through restricted passages 228, and liquid may be drawn into the

lower portion of cylinder compartment 222 through restricted inlet passage 236. After predetermined movement of solenoid core 210, however, the outwardly extending projection 215 of latch lever 214 engages integral stop 217 on frame supporting plate 196, to release the solenoid core from the time delay sleeve 216. This permits the core to rise rapidly into engagement with shoulder 208 on the contact rod and separate the contacts.

It will be noted that the lower end of time delay sleeve 216 is notched as at 244, and carries a latch lever 246 adapted to engage beneath integral shoulder 248 on contact rod 204, when the contact is adjacent the upper limit of its movement. Latch lever 246 is normally biased in a direction to engage shoulder 248, by a spring 250. Therefore, upon attempted movement of contact rod 204 in a downward direction to reclose the breaker contacts, this motion is impeded by valve member 224 which now has the passages 228 therethrough closed off by valve 230, so that all of the liquid therebelow in chamber 222 must be displaced through the relatively small clearance between the valve piston and cylinder chamber wall. Accordingly, a time delay is interposed between the circuit interrupting operation and reclosure of the circuit breaker contacts, until extension 252 on latch lever 246 engages integral stop 254 on supporting plate 196, to disengage the latch from contact rod shoulder 248 to permit quick reclosure of the contacts.

It will be noted that in the circuit closing operation a certain amount of the liquid contained in the lower part of cylinder compartment 222 will be forced through passages 256 in transverse supporting wall 200, to force lockout piston 226 downwardly a predetermined distance. In the event of a continuing fault on the circuit, lockout piston 226 will be forced downwardly a predetermined distance by each successive reclosure of the breaker contacts, until finally the inclined surface 238 thereof engages lockout lever 240 to move it in a clockwise direction about its pivot 241, into engagement with notch 244 on time delay sleeve 216, to thereby prevent movement of the same and contact rod 204 downwardly to a closed circuit position. Of course, if at any time before the predetermined number of reclosures of the breaker necessary to lock the contacts open, the fault clears, then lockout piston 226 will be slowly reset by coil spring 227 to its normal position shown in Fig. 8.

It will be noted that in this embodiment of the invention, a single time delay means is provided for both giving inverse time current characteristics on a circuit interrupting operation, and for delaying reclosing of the breaker contacts after an interrupting operation, and that this time delay means has different characteristics for these two operations, respectively; that is, the valve member 224 presents greater resistance in downward movement in compartment 222 by virtue of closure of valve 230, than its resistance to upward movement in cylinder compartment 222, because on this latter movement valve 230 is opened as well as inlet check valve 234.

In the foregoing there have been described several embodiments of the present invention incorporated in automatic reclosing circuit breakers of the fluid type, which are adapted to automatically reclose the circuit a predetermined number of times, after which the breaker con-

tacts are automatically locked in an open circuit position, such as to require a manual operation to restore the breaker to operative condition.

Having described preferred embodiments of the invention in accordance with the patent statutes, it is desired that the invention be not limited to the particular embodiments herein disclosed, inasmuch as it will be obvious, particularly to persons skilled in the art, that many modifications may be made in these particular embodiments without departing from the broad spirit and scope of the invention.

We claim as our invention:

1. In a circuit interrupter, cooperating contact means, at least one of which is mounted for movement into and out of engagement with the other of said contact means, means having lost motion with said movable contact means for moving said movable contact away from the other of said contact means, means for locking said movable contact means in engagement with the other of said contact means including a locking lever biased to lock said movable contact means closed, said lever having a portion positioned to be engaged by said contact moving means after predetermined movement thereof in a direction to separate said contact means, time delay means, drive means movable with said movable contact means and biased to engage said time delay means, means permitting engagement of said drive means and time delay means adjacent the end of movement of said movable contact means away from said cooperating contact means, and means for disengaging said drive means and time delay means adjacent the end of contact closing movement of said movable contact means.

2. In a circuit interrupter, contact means mounted for movement into and out of engagement with cooperating contact means, means having lost motion with said movable contact means for moving said movable contact away from said cooperating contact means, means for locking said movable contact means in engagement with said cooperating contact means, said contact moving means adapted to release said locking means after predetermined movement thereof in a direction to separate said contact means, time delay means, drive means movable with said movable contact means and biased to engage said time delay means, means permitting engagement of said drive means and time delay means adjacent the end of movement of said movable contact means away from said cooperating contact means, and means for disengaging said drive means and time delay means adjacent the end of contact closing movement of said movable contact means.

3. In a circuit interrupter, contact means mounted for movement into and out of engagement with cooperating contact means, means having lost motion with said movable contact means for moving said movable contact away from said cooperating contact means, means for locking said movable contact means in engagement with said cooperating contact means, said contact moving means adapted to release said locking means after predetermined movement thereof in a direction to separate said contact means, time delay means controlling movement of said contact moving means, second time delay means, drive means movable with said movable contact means and biased to engage said second time delay means, means permitting engagement

of said drive means and second time delay means adjacent the end of movement of said movable contact means away from said cooperating contact means, and means for disengaging said drive means and second time delay means adjacent the end of contact closing movement of said movable contact means.

4. In a circuit interrupter, contact means mounted for movement into and out of engagement with cooperating contact means, means having lost motion with said movable contact means for moving said movable contact away from said cooperating contact means, time delay means, means for releasably coupling said time delay means solely to said contact moving means, and means for releasing said coupling means after predetermined movement of said contact moving means in a direction to separate said contact means.

5. In a circuit interrupter, contact means mounted for movement into and out of engagement with cooperating contact means, means having lost motion with said movable contact means for moving said movable contact away from said cooperating contact means, time delay means, means for releasably coupling said contact moving means and time delay means, second means for releasably coupling said movable contact means and time delay means, means for releasing said first coupling means in response to predetermined movement of said contact moving means in a direction to separate said contact, and means for releasing said second coupling means upon predetermined movement of said movable contact means in a direction to engage said cooperating contact means.

6. In a circuit interrupter, contact means mounted for movement into and out of engagement with cooperating contact means, means having lost motion with said movable contact means for causing movement of said movable contact away from said cooperating contact means, single time delay means, means for directly connecting said time delay means solely with said contact moving means so that said time delay means is operated in one way to control movement of said contact moving means upon movement thereof in a direction to open said contact means, and said time delay means is operated in another way to control reclosing movement of said movable contact means, and said time delay means having means responsive to operation thereof in the aforesaid different ways to provide for different time delaying characteristics in the control of said two movements, respectively.

7. In a circuit interrupter, contact means mounted for movement into and out of engagement with cooperating contact means, means having lost motion with said movable contact means for moving said movable contact away from said cooperating contact means, time delay means adapted to control movement of said contact moving means upon movement thereof in a direction to open said movable contact means, and adapted to control reclosing movement of said movable contact means, means for disconnecting said contact moving means from said time delay means after predetermined movement of said contact moving means in a direction to separate said contact means, and means for disconnecting said movable contact means and time delay means in response to predetermined movement of movable contact means towards said cooperating contact means.

8. In a circuit interrupter, contact means mounted for movement into and out of engagement with cooperating contact means, means having lost motion with said movable contact means for moving said movable contact away from said cooperating contact means, time delay means independent of any electrical condition of the circuit associated with said contact moving means for delaying movement thereof, second time delay means, drive means movable with said movable contact means and biased to engage said second time delay means, means permitting engagement of said drive means and second time delay means adjacent the end of movement of said movable contact means away from said cooperating contact means, and means for disengaging said drive means and second time delay means adjacent the end of contact closing movement of said movable contact means.

9. In a circuit interrupter, contact means mounted for movement into and out of engagement with cooperating contact means, means having lost motion with said movable contact means for causing movement of said movable contact away from said cooperating contact means, time delay means, means for directly connecting said time delay means solely with said means for causing contact movement at least during a circuit opening operation for delaying movement thereof at least in a direction to cause separation of said contact means, and second time delay means mechanically connected with said movable contact means at least during a circuit closing operation thereof for delaying closing movement.

10. In a circuit interrupter, contact means mounted for movement into and out of engagement with cooperating contact means, means having lost motion with said movable contact means for moving said movable contact away from said cooperating contact means, time delay means adapted to control movement of said contact moving means upon movement thereof in a direction to open said movable contact means, and adapted to control reclosing movement of said movable contact means, means for rendering said time delay means inoperative to delay movement of said contact moving means in a direction to open said movable contact means after predetermined movement of said contact moving means in a direction to separate said contact means, and means for rendering said time delay means inoperative to delay closing movement of said movable contact means in response to predetermined movement of movable contact means towards said cooperating contact means.

11. In a circuit interrupter, contact means mounted for movement into and out of engagement with cooperating contact means, means having lost motion with said movable contact means for moving said movable contact away from said cooperating contact means, time delay means independent of any electrical condition of the circuit, means for directly connecting said time delay means solely with said contact moving means so as to control movement of said contact moving means upon movement thereof in a direction to open said contact means, and to control reclosing movement of said movable contact means, and means for rendering said time delay means ineffective to delay closing movement of said movable contact means in response to predetermined movement of said mov-

able contact means towards said cooperating contact means.

12. In an automatic reclosing circuit breaker, separable contacts, means responsive to predetermined electrical conditions including a part having lost motion with respect to said contacts for causing separation of said contacts, said contacts being biased into engagement to automatically reclose said contacts after a circuit interrupting operation, and a single time delay means, means for mechanically connecting said time delay means with part of the breaker so that said time delay means is operated in one way for delaying opening movement of said contacts for a predetermined time after the occurrence of said predetermined conditions, and said time delay means is operated in another way for delaying closing movement of said contacts, and said time delay means having means responsive to operation thereof in said other way for changing the time characteristic thereof.

13. In an automatic reclosing circuit breaker, separable contacts, means responsive to predetermined electrical conditions for causing separation of said contacts and having lost motion relative to said contacts, said contacts being biased into engagement to automatically reclose after a circuit interrupting operation, and time delay means independent of any electrical condition of the circuit, means to mechanically connect said time delay means solely with said condition responsive means during a circuit opening operation for delaying opening movement of said contacts for a predetermined time after the occurrence of said predetermined conditions, a second time delay means, and means to mechanically connect said second time delay means with said contacts for delaying reclosure of said contacts for a predetermined time after a circuit interrupting operation.

14. In an automatic reclosing circuit breaker, separable contacts, means responsive to predetermined electrical conditions for causing separation of said contacts and having lost motion relative to said contacts, said contacts being biased into engagement to automatically reclose after a circuit interrupting operation, and time delay means releasably mechanically connected with said condition responsive means during only an initial part of the relative movement of said condition responsive means, means for disconnecting said time delay means and condition responsive means at the end of said part of relative movement, whereby said time delay means is effective to delay separation of said contacts a predetermined time after the occurrence of said predetermined conditions after which said contacts are separated at a relatively rapid rate.

15. In a circuit interrupter, a movable contact actuating rod, a contact actuatable by movement of said rod into and out of engagement with a cooperating contact, fluid dashpot means having a movable member slidably mounted on said rod, spaced means limiting relative sliding movement of said member on said rod, actuating means operative to move said member in one direction, said member biased to move in the opposite direction to one limit of its relative

sliding movement on said rod, and said dashpot means having means for rendering said dashpot means ineffective to delay movement of said actuating means in response to predetermined relative sliding movement of said member on said rod, whereby said contact is rapidly moved away from said cooperating contact only a predetermined time after said actuating means is energized.

16. In a circuit interrupter, a movable contact actuating rod, a contact actuatable by movement of said rod into and out of engagement with a cooperating contact, fluid dashpot means having a tubular piston member slidably mounted on said rod and a relatively stationary dashpot cylinder receiving said piston member, spaced means limiting relative sliding movement of said member on said rod, actuating means operative to move said member in one direction, said member biased to move in the opposite direction to one limit of its relative sliding movement on said rod, and said dashpot means having means for rendering said dashpot means ineffective to delay movement of said actuating means in response to predetermined relative sliding movement of said member on said rod, whereby said contact is rapidly moved away from said cooperating contact only a predetermined time after said actuating means is energized.

17. In a circuit interrupter, contact means mounted for movement into and out of engagement with cooperating contact means, means having lost motion with said movable contact means for causing movement of said movable contact away from said cooperating contact means, single time delay means, means for directly connecting said time delay means solely with said contact moving means so as to control movement of said contact moving means upon movement thereof in a direction to open said contact opening means, and to control reclosing movement of said movable contact means, and said time delay means having means responsive to the direction of movement of said contact moving means to vary the resistance to the aforesaid movements depending on the direction thereof.
